UNITED STATES PATENT OFFICE.

EDWARD B. ALLEN, OF PORTLAND, MAINE, ASSIGNOR TO THE SINGER
MANUFACTURING COMPANY, OF NEW JERSEY.

CLAMP FOR BUTTON-HOLE SEWING-MACHINES.

SPECIFICATION forming part of Letters Patent No. 439,087, dated October 28, 1890.

Application filed January 9, 1890. Serial No. 336,334. (No model.)

To all whom it may concern:

Be it known that I, EDWARD B. ALLEN, of 5
Portland, county of Cumberland, State of
Maine, have invented an Improvement in
Clamps for Button-Hole Work, of which the
following description, in connection with the
accompanying drawings, is a specification,
like letters and figures on the drawings repre- 10
senting like parts.
The material, leather or cloth, to have but-
ton-holes overstitched therein is now com-
monly held in a clamp, which is moved under
the needle of the stitch-forming mechanism,
and this clamp in many machines has a slid- 15
ing movement and a partial rotation. When
the stitching for a button-hole has been fin-
ished, the machine is stopped and the oper-
ator breaks or cuts the needle-thread near
the clamp and holds the broken end, and 20
with his other hand on the needle-thread
at the other side of the needle he draws from
the tension device a sufficient quantity of
thread and pulls it through the eye of the
needle to thus have sufficient thread to start 25
the button-hole next to be stitched. In doing
this the operator commonly draws from the
tension device much more thread—usually
silk, and expensive—than is needed to start
the next button-hole, and in practice very 30
much silk is wasted, the waste being esti-
mated as high as seven per cent. To obviate
this waste of silk, and to also economize time,
I have provided a cloth-clamp with a thread
clamp or jaw, and also with a cutter to auto- 35
matically sever the needle-thread close to the
finished end of the button-hole, the thread-
clamp holding the said thread while the ma-
terial is changed in the cloth-clamp, the said
thread-clamp holding the end of the said 40
thread at the proper side of the eye of the
needle until after the stitching for another
button-hole has been commenced.

Believing myself to be the first to devise
means to hold and cut the needle-thread be- 45
tween the material held in the cloth-clamp
and the needle, I desire it to be understood
that I do not intend to limit my invention to
the particular thread-clamp shown or to the
particular cutter shown, nor do I desire to 50
limit my invention to the application of a

thread clamp and cutter or to the particular
form of cloth-clamp herein shown.

One feature of my invention therefore con-
sists in a cloth-clamp and a traveling co-op-
erating thread-clamp to seize and clamp the 55
needle-thread between the material in the
cloth-clamp and the eye of the needle after
the completion of the stitching for a button-
hole and before the material is removed from
the clamp.

Another feature of my invention consists in
the combination, with a cloth-clamp and a
thread-clamp to hold the needle-thread be-
tween the cloth-clamp and the eye of the
needle, of a thread-cutter to cut the said 65
needle-thread between the thread-clamp and
the material held in the cloth-clamp.

Other auxiliary features of my invention
will become apparent in the following de-
scription and claims at the end thereof.

Figure 1 is a top or plan view of one well-
known form of cloth-clamp with my improve-
ments added thereto, the parts being in the
position they will occupy when the machine
is to be started to stitch a button-hole in ma- 75
terial held in usual manner in the cloth-
clamp. Fig. 2 is a partial side elevation
thereof, showing part of the usual eye-pointed
needle with the thread extended therefrom to
the thread-clamp, the upper jaws of the cloth- 80
clamp and the parts for supporting and mov-
ing them being omitted. Fig. 3 is a detail
with the cap shown in Figs. 1 and 2 removed,
the said figures also showing a piece of ma-
terial with a slit cut therein for a button-hole 85
next to be overstitched. Fig. 4 is a detail
with the slide of Fig. 3 removed to show the
thread-cutter under it. Fig. 5 is an elevation
from the left of Fig. 2, the needle being omit-
ted; and Figs. 6 and 7 are details to be re- 90
ferred to.

The base a of the cloth-clamp, the later-
ally-movable jaws a' , on which the material
to be stitched rests, the lever a^2 , to move the
said jaws away from each other to expand 95
the slit s^2 of the material s^3 , the arms a^3 , con-
nected by screws a^5 to the blocks a^4 , having
their fulcrum studs a^6 in ears a^7 , connected
to the rear ends of the jaws a' , part of one of
the said ears being broken off in Fig. 2, the 100

rack-shaft b , having an attached lever b' at one end and provided between its ends with a crank, which is embraced in usual manner by a link b^2 , surrounding at its upper end 5 a yoke b^3 , which connects the arms a^3 , the wedge-blocks b^4 , attached to the arms a^3 by screws b^5 , the arms a^3 being normally kept elevated by springs under them, the top jaws b^6 of the cloth-clamp, pivoted on the arms a^3 , 10 the stand b^7 , forming a rigid part of the base a and bored to receive the vertical pin b^8 , which in practice enters a slot in the bed-piece of the machine and then a groove in a cam under the bed-piece, and the spring a^{10} , to 15 normally keep the said pin depressed, are or may be all as usual in cloth-clamps, the particular cloth-clamp thus far referred to being that commonly used in the "Singer" button-hole machine.

20 In accordance with my invention I provide the clamp with two arms $c c'$, having holes at their right-hand ends, viewing Figs. 1 and 2. The end of the rock-shaft b is bored for the reception of a stud-screw c^2 , to form a pivot 25 for said arm c . The rock-shaft b has applied to it at its opposite end, between the ear a^7 and the lever b' , the other arm c' . These arms $c c'$ are extended beyond the end of the base a of the usual cloth-clamp, and their 30 outer ends are connected by a web c^3 , (see Fig. 4,) having a cam-slot 33 and screw-holes 2. The web c^3 at each edge has secured to it in any usual way a gib c^4 , the said gibbs being undercut at their inner edges to form a dove-tailed space (see Fig. 5) for the reception of 35 a slide d , the edges of which next the gibbs are shaped to fit between the edges of the gibbs. The gibbs have holes 3 for the reception of screws 4, by which to attach to them 40 a cover-plate d' , having a slot 5, up through which projects a pin 6, carried by a switch block or dog d^2 , adapted to turn on a pivot 10, held by the cap-plate and extended down below it. The pin 6 is acted upon by a spring 45 7, shown as held on the cap-plate by a screw 8, the spring 7 normally keeping the point of the switch in the position shown in Fig. 3.

The slide d has at its end next the button-hole to be stitched a jaw e , (shown best in Fig. 50 3,) it being shown as fixed. The slide d has a second jaw (shown as a lever e') pivoted at 12 on the said slide and provided at its left-hand end, viewing Fig. 3, with a roller or other stud e^2 , a spring e^3 normally acting to keep 55 the short arm of the jaw e' pressed against the jaw e to thus hold fast the needle-thread grasped between them. The jaws $e e'$ constitute one form of thread-clamp. The slide d has a stud 13 extended below it. (See Figs. 50 3 and 4, the stud in Fig. 4 being supposed to be a section.) This stud 13 serves as the fulcrum for the thread-cutter f . (Shown by full lines, Fig. 4, by dotted lines, Fig. 3, and separately in Fig. 7.) This cutter has a pin 14 extended down from its lower side into the slot 33, the cutting-edge 15 of the said cutter normally standing, while a button-hole is being

stitched, close to the inner beveled edge of the thread-clamping jaw e .

The slide d has connected to it by screw 16 70 a bar 17, which is jointed at 18 to a link 19, pivoted at 20 on an upright 21, erected on the stand b^7 , the said link 19 having, as shown, a slot 22, which is entered by a pin 23 of an arm 24, which I have added to the lever 25, which, 75 except for said arm, is the same as in the usual cloth clamp referred to, the said arm at its left-hand end resting just below the head 26 of the pin b^8 , before referred to.

The arms $c c'$ are slotted to receive in them 80 the pivot-pins which secure the clamping-jaws b^6 to the ends of the arms a^3 , so that as the said arms are lifted by the lever b' to remove the cloth from the cloth-clamp the arms $c c'$ and their attached parts are also lifted to 85 turn about the shaft b as a center.

When the button-hole has been overstitched in the material clamped in the cloth-clamp, the operator stops the machine, and with his finger on the lever 25 depresses it to lift the 90 pin b^8 preparatory to reversing the clamp or bringing it back into starting position to have its jaws opened and the material removed and put back again with another slitted portion of the material in place to be stitched. Now, 95 as the operator depresses the lever 25 to raise the pin b^8 he also draws the slide d to the right, and in so doing the roller-stud e^2 acts on the switch or dog d^2 , which causes the jaw e' to be turned in the direction to carry its 100 short end away from the stationary jaw e , the said open jaws acting as the thumb and finger of the operator to cross and embrace the needle-thread between the work held in the cloth-clamp and the eye of the needle n , and 105 as soon as the roll e^2 passes the switch or dog the spring e^3 acts to clamp the thread-clamping jaws on the needle-thread. As the slide d is moved forward, as described, the pin 110 14 of the thread-cutter f , acting in the slot 33, turns the thread-cutter on its pivot 13 and cuts the needle-thread off between the thread-clamp and the work held in the clamp. The thread-clamp holds the needle-thread as 115 the cloth-clamp is reversed, and while the jaws of the cloth-clamp are opened for the removal of the work or its change of position therein, and while the cloth-clamp is closed the thread-clamp retaining the end of the needle-thread until after the stitching has 120 been started for another button-hole. The operator releases the lever 25 as soon as the clamp has been reversed, and the spring a^{10} , through the pin b^8 , turns the lever 25 in the opposite direction, the slide d at such time 125 being moved back into its normal position, Fig. 3; but in going back into such position the roller-stud e^2 passes between the switch d^2 and the gib next to it, the switch yielding and leaving the thread-clamp closed on 130 the needle-thread. The thread-clamp, as herein shown, holds the needle-thread until the operator again depresses the lever 25; but it is not essential to hold the said thread after

one or two stitches, although it does no harm to hold it until the thread-clamp is to be again actuated to grasp the needle-thread at the completion of another button-hole.

- 5 The button-hole-stitching machine with which the needle-thread clamping device and needle-thread cutter are used will in practice have suitable devices whereby the thread-tension will be relaxed when the cloth-clamp 10 stops, so that the usual devices for controlling the needle-thread between the tension and needle—as, for instance, the take-up and a slack-thread controller—will not act to pull the needle-thread out or away from the clamp. 15 It will be obvious to one skilled in the art that the particular shape of the thread-clamping jaws and the cutter may be modified very considerably without departing from my invention, and the devices employed for moving the thread-clamping jaws and cutter might be also varied very considerably in shape, according to the particular shape of the cloth-clamp holding the material to be overstitched, as it is well known that in some 25 classes of button-hole-stitching machines the clamp does not rotate.

I have shown the slide carrying the thread-clamping devices as moved by the lever 25. I have selected that part of the clamp herein 30 shown as the actuating means for the slide or thread-clamp because that lever must be moved after the completion of each button-hole, and when my invention is applied to any other usual form of cloth-clamp I shall 35 select as the actuating device for the thread-clamp to move it toward and to grasp the needle-thread, as described, between the needle and the clamp any part of the said cloth-clamp which always has to be moved in 40 clamping and unclamping the material, the particular part or parts of such other well-known form of clamp or device co-operating therewith from which to derive movement for the thread-clamp, as described, being left 45 to the judgment of the builder of the machine.

I claim—

1. A work or cloth clamp for a button-hole sewing - machine, provided with the usual clamping-jaws, said work-clamp having thereon a traveling thread-clamp adjacent to said jaws and being thus adapted to grasp and hold the needle-thread between the work held in said jaws and the needle. 50

2. A work or cloth clamp for a button-hole sewing - machine, provided with the usual clamping-jaws, said work-clamp having thereon a thread-clamp adjacent to said clamping-jaws, combined with a thread-cutter arranged between the said thread-clamp and the point 55 at which the material is held by the said clamping-jaws, whereby the needle - thread may be severed close to the work when a button-hole is completed and then be held by the said thread-clamp while the work-clamp 60 is reversed and until after the stitching of the subsequent button-hole is commenced. 65

3. A cloth-clamp and a slide, as *d*, having thread-clamping devices, combined with devices to connect the said slide with a part of 70 the cloth-clamp which is moved between the time that one button-hole is finished and another commenced and devices to effect the opening and closing of the said thread-clamp, substantially as described. 75

4. A cloth-clamp and a slide, as *d*, having thread-clamping devices, combined with devices to connect the said slide with a part of the cloth-clamp which is moved between the time that one button-hole is finished and another commenced and devices to effect the opening and closing of the said thread-clamp, 80 a cutter to cut the needle-thread, and actuating devices for the said cutter, substantially as described. 85

In testimony whereof I have signed my name to this specification in the presence of two subscribing witnesses.

EDWARD B. ALLEN.
